UNITED STATES PATENT OFFICE.

SAMUEL TOLES, OF PASADENA, CALIFORNIA, ASSIGNOR TO CROWN GAS RADIATOR COMPANY, OF PASADENA, CALIFORNIA, A PARTNERSHIP CONSISTING OF ARTHUR BETZ, H. J. FISHER, AND HIMSELF.

GAS RADIATOR.

Application filed December 3, 1921. Serial No. 519,613.

To all whom it may concern:

Be it known that I, SAMUEL TOLES, a citizen of the United States, residing at Pasadena, in the county of Los Angeles and State 5 of California, have invented certain new and useful Improvements in Gas Radiators, of which the following is a full, clear, and exact specification.

This invention relates to gas radiators or 10 heaters and has for its object to provide a sectional radiator of the general form and shape of a hot water or steam radiator but in which gas jets are used as the heating medium.

15 A special object is to secure improved circulation of the heated air in a radiator of this kind, whereby its heating efficiency is increased and less of the heat developed by the burner lost through the discharge vent. 20 Other objects will appear as the description proceeds.

The invention will be first hereinafter described in connection with the accompanying drawings, which constitute part of this 25 specification, and then more specifically defined in the claims at the end of the description.

In the accompanying drawings, wherein similar reference characters are used to 30 designate corresponding parts throughout the several views:

Figure 1 is a front elevation of a radiator constructed substantially in accordance with this invention.

35 Figure 2 is an end elevation of the same.

Figure 3 is a rear elevation of the radiator.

Figure 4 is a vertical section taken on the line IV—IV of Figure 2.

Figure 5 is a vertical section taken on the line V—V of Figure 1, and

Figure 6 is a vertical section taken on the line VI—VI of Figure 1.

The radiator may consist of two end sections 1 and 2, an intermediate vent section 3, and any desired number of filler sections 4 arranged between said end sections and vent section. All of the sections communicate with one another near the bottom through passages 5 and near the top through passages 6, said passages being formed by interfitting collars 7 and 8, respectively. Between the passages 5 and 6, the sections of the radiator are spaced apart, as at 9 in Figs. 1, 3 and 4. Bolts 10 are passed through all

of the sections near the top and bottom of the radiator for fastening said sections together, said bolts being preferably arranged in the passages 5 and 6.

The end sections 1 and 2 are made alike, each having legs 11 for supporting the radiator above the floor. As illustrated best in Fig. 5, the end sections have transverse passages 12 formed therein through which air may freely pass from the ends of the radiator into the spaces 9 between said end sections and the adjacent filler sections 4. As shown, there are four of these air passages 12 in each end section, two being arranged side by side about midway of the height of the section, while the other two are disposed side by side nearer the top of the section and in vertical alignment respectively with the lower two. An inclined partition 13 extends from the top wall of the lower rear passage 12 to the bottom wall of the upper front passage 12, and an arched partition 14 joins the upper end walls of the two upper passages 12, preferably following the line of the upper edge of the passage 6. Another partition 15 of angular form extends from the bottom wall of the lower rear passage 12 to the rear wall of the section forming a moisture trap 16. The base of each end section also serves as a moisture trap 17. An air inlet opening 18 is formed in the inner wall of each end section and from said opening the air circulates in each of said sections as indicated by the arrows in Figs. 4 and 5.

A gas burner consisting of a pipe 19 extends through the passages 5 and has a pair of openings 20 and 21 for flame jets arranged centrally of each radiator section. A lighting opening 22 is provided in the outer end wall of the section 2 just above the burner pipe 19, said opening being normally closed by a swiveled cover plate 23 as shown in Figs. 2 and 4. Said burner pipe extends through said outer end wall of the section 2 and terminates near the outer end wall of the end section 1, being supported on a suitable lug 40 projecting inwardly from said latter wall. Outside of the radiator the burner pipe is fitted with the usual air mixer 41 and valve 42.

The jet openings 20 in the burner pipe are arranged centrally of the top thereof, while the jet openings 21 are arranged ap-

proximately 45 degrees in front of said openings 20, so that the jets of flame from the openings 20 extend directly upwardly between the walls of the two lower passages 12 in the end and filler sections, while the jets of flame from the openings 21 are directed below the walls of the front lower passages 12 in said sections. This arrangement of the jet openings in the burner pipe facilitates the circulation of the heated air on both sides of the walls of said front lower passage 12 in each section, as shown in Fig. 5. The air which passes upwardly between the walls of the two lower passages 12 in each of the end and filler sections is deflected to the front of the walls of the upper front passage 12 by the inclined partition 13, so that the two currents of air rising at opposite sides of the walls of the lower front passage 12 are united above the same and together flow between the walls of the front upper passage 12 and the front wall of the section. The heated air then travels rearwardly over the arched partition 14, then downwardly between the rear wall of the section and the walls of the upper rear passage 12 and then upwardly above the inclined partition 13 and between the walls of the two upper passages 12, finally escaping to the adjacent filler section through the passage 6.

The filler sections 4 are constructed like the end sections 1 and 2, except that the legs 11 are omitted, as well as the air inlet openings 18. The air enters said filler sections from the end sections and also from the vent section 3 through the passages 5, and circulates through said filler sections in the same manner as already described in connection with the end sections.

The intermediate vent section 3, as best illustrated in Fig. 6, has an air inlet opening 24 in its lower end and a long transverse air passage 25 arranged in line with the right hand upper and lower passages 12 of the end and filler sections, said passage 25 in the vent section extending from the level of the top of said upper passage 12 to near the level of the lower end of said lower passage 12. The walls of said passage 25 merge at their lower ends into a transverse partition 26 extending above the burner pipe 19 to the rear wall of the section. The upper ends of the walls of the passage 25 merge into a curved partition 27 extending around the upper edge of the passages 6 leading from the adjacent filler sections. A vent opening 28 is formed in the rear wall of the vent section about midway of the vertical extent of the passage 25 and some distance above the transverse partition 26, so that said partition with the side walls of the vent section, form a moisture trap 29. Said vent opening 28 may be connected to a chimney by a suitable pipe, not shown. The air

inlet opening 24 in the bottom of the vent section has walls extending some distance upwardly on the inside of said section to form a moisture trap 30 around said walls.

From the rear wall of the vent section 70 above the vent opening 28 a partition 31 extends inwardly and upwardly, as shown in Fig. 6, terminating slightly below and to the rear of the rear end of the curved partition 27, thus leaving a passage 32 between said partitions 31 and 27 for the downward circulation of air. The partition 31, together with the rear and side walls of the section 3, forms another moisture trap 33. A downwardly extending vane or partition 80 34 is joined to the partition 31 and terminates about midway of the vertical extent of the vent opening 28.

The air which enters the vent section through the opening 24, after being heated 85 by the jets of flame from the openings 20 and 21 in the burner pipe 19, is deflected by the transverse partition 26 and caused to pass upwardly in front of the wall of passage 25. At the top of the vent section, the 90 air passes rearwardly over the curved partition 27, then downwardly at the rear of said curved partition, through the passage 32 and continues downwardly in front of the partitions 31 and 34 and in the rear of the walls 95 of passage 25, finally passing rearwardly to the vent opening 28 below the lower end of said partition 34. The spent air from the other sections of the radiator enters the vent section through the passage 6 and joins the 100 downward current of air flowing to the vent opening 28 between the partitions 31 and 34 and the walls of the passage 25.

It will thus be seen that with the arrangement of the walls of the transverse air passages through the sections of the radiator and the various partitions in said sections, as herein described, the heated air is caused to circulate thoroughly in each section before escaping through the vent opening in 110 the vent section. It will be further noted that the arrangement of the jet openings 20 and 21 in the burner pipe is such as to insure the circulation of the air in the end and filler sections at both sides of the walls of 115 the front lower transverse air passages 12, so that practically all of the radiating surfaces of said sections are heated with the result that the efficiency of the radiator is raised to the maximum degree.

I claim:

1. In a gas radiator, the combination with end sections and a vent section arranged between said end sections, there being communicating passages leading from said end sections into said vent section near the upper ends thereof, of a burner arranged in and communicating with the interior of the lower end portion of each of said end and vent sections, said vent section having an 130

air inlet in its base portion and a vent opening in its side, and partitions in said vent section for causing the air to travel to its top from the inlet in its base before 5 escaping through said vent opening in its side.

2. In a radiator of the character described, the combination with a vertical hollow body having an air outlet, of a burner 10 below said outlet, a transverse partition extending from one side of the body between the burner and outlet and terminating in spaced relation to the opposite side of said body, another transverse partition arranged 15 above the outlet passage, a vertical partition extending from the end of the lower transverse partition, which is spaced from the side of the body, to the corresponding end of the upper transverse partition, and 20 another vertical partition arranged below the lower transverse partition and spaced therefrom for dividing the heated air into separate currents in the lower portion of the body, said air currents being combined 25 above said last mentioned vertical partition by the lower transverse partition and being directed upward at one side of the body and across the top thereof by the other partitions before reaching the outlet.

3. In a radiator of the character described, the combination with a vertical hollow body having an air outlet, of a burner 30 below said outlet, a transverse partition extending from one side of the body between the burner and outlet and terminating in spaced relation to the opposite side of the body, another transverse partition arranged above the outlet passage, a vertical partition extending from the end of the lower 35 transverse partition, which is spaced from the side of the body, to the corresponding end of the upper transverse partition, another vertical partition depending from the other end of the upper transverse partition, and still another vertical partition arranged below the lower transverse partition and spaced therefrom for dividing the heated air into separate currents in the lower portion of the body, said air currents 40 being combined above said last mentioned vertical partition by the lower transverse partition and being directed upward at one side of the body, across the top thereof and down the other side of the body by the other 45 partitions before reaching the outlet.

4. In a radiator of the character described, the combination with a vertical hollow body having two air inlets in the upper and lower portions thereof respectively, and 50 an air outlet arranged between said inlets, of a burner communicating with the interior of the body and arranged below the outlet,

let, and partitions in said body for causing the air from the lower inlet after being heated by the burner to pass up one side of 65 the body, across said body above the upper inlet and down the other side of the body before reaching the outlet, the air from the upper inlet and the downward current of air from the lower inlet passing downward 70 through the center of the body to said outlet.

5. In a radiator of the character described, the combination with a vertical hollow body having two air inlets in the upper and lower portions thereof respectively, and 75 an air outlet arranged between said inlets, of a burner communicating with the interior of the body and arranged below the outlet, a transverse partition between the burner and outlet for causing the air from the 80 lower inlet after being heated by the burner to pass upward at one side of the body, a vertical partition extending upwardly from said transverse partition, and another transverse partition extending from the upper end of said vertical partition above the upper inlet, whereby the upward current of air from the lower inlet is directed across the upper portion of the body and down the other side thereof before reaching the outlet. 85

6. In a radiator of the character described, the combination with a vertical hollow body having two air inlets in the upper and lower portions thereof respectively, and 90 an air outlet arranged between said inlets, of a burner communicating with the interior of the body and arranged below the outlet, a transverse partition between the burner and outlet for causing the air from the lower inlet after being heated by the burner to pass upward at one side of the body, a vertical partition extending upwardly from said transverse partition, another transverse partition extending from the upper end of said vertical partition above the upper inlet, 95 whereby the upward current of air from the lower inlet is directed across the upper portion of the body and down the other side thereof before reaching the outlet, another substantially vertical partition spaced from the upper transverse partition and extending downward below the upper end of the outlet, and another transverse partition extending from said last mentioned vertical partition to the side of the body over the 100 outlet, whereby the air from the upper inlet and the downward current of air from the lower inlet are caused to pass downwardly through the center of the body before reaching the outlet. 105

In testimony whereof I have signed my name to this specification.

SAMUEL TOLES.
